METHOD OF PRODUCING A FIXED GAS

Charles B. Hillhouse, New York, N. Y., assignor
to Sylvia Remsen Hillhouse, New York, N. Y.

Application July 19, 1937, Serial No. 154,518

1 Claim. (Cl. 48—214)

This invention relates to a method and apparatus for fixing gas and, more particularly in such method, to a feature of providing a shield of steam adjacent an inlet of hot oil gas, which shield is effective to prevent any deposit of free carbon upon the walls of the chamber into which the hot oil gas is supplied.

An object of the invention is to provide a method and apparatus for making a fixed gas wherein hot oil gas is supplied to a chamber, and then heated up to a gas fixing temperature, the method being carried out in an apparatus arranged to permit a continuous cycle of higher temperature gas to transfer a portion of its sensible heat 15 in heating up the lower temperature gas mixed into it in the production of fixed gases.

Another object of the invention is to provide in a gasoline making device a novel means and method of producing a shield in the form of a sleeve of steam positioned to surround the stream of admitted hot oil gas whereby to prevent any deposit of free carbon on the chamber wall adjacent the inlet of hot oil gas and then to extract the free carbon from the cycle of fixed 25 gases.

In the accompanying drawing—

Fig. 1 is a view, partly in section, of an apparatus adapted to provide a continuous cycle of gas fixing;

Fig. 2 shows a sectional view on line 2—2 of Fig. 1; and

Fig. 3 is a view, partly in section, of an apparatus, wherein gases of combustion are continuously supplied to form gasoline.

The main feature of invention herein disclosed is related to my application, Serial No. 61,071, filed January 27, 1936, which has matured into Patent No. 2,162,433, June 13, 1939, but differs therefrom particularly as to the method and means for supplying and maintaining a shield of steam to surround the stream of admitted hot oil gas.

In accordance with the disclosure of this application, I provide a main chamber 1 of an endless type or closed tubular chamber. A supply of hot oil gas at about 700° F. is injected into a cycle of higher temperature gas in this chamber by means of a spray head 2 adapted to project this gas in the form of a fine spray. The spray head 2 receives its gas supply from a conduit 3 which may be fed from a blower under pressure.

A portion 4 of the chamber 1 is provided with double walls 5 and 6 adjacent the spray head 2 to define a chamber 7. A supply of steam is admitted through a conduit 8 and valve 9 to the

chamber 7. The inner wall 5 of the chamber 7 is formed of a porous refractory material that will permit a slow continuous feed of steam through the wall 5 whereby to maintain a layer of heated steam closely adjacent the inner side of the wall 5. This layer of heated steam will act as a coating on this inner wall and serve as a shield between the stream of hot gas from spray head 2 mixed into the cycle of higher temperature gas and the wall 5. If there should be any free carbon in this stream of hot gas or in the stream of gas passing around the chamber 1 due to cracking or other sources, this carbon cannot reach or adhere to the inner wall 5 because of this coating or sleeve of steam. All or part of such free carbon will be instantly gasified by the heated steam in case of contact therewith. The steam oozing through the wall 5 will produce a steam current towards the gas stream and tend to push any free carbon that is not gasified away from this wall.

The stream of hot oil gas after passing through the chamber 4 will pass through another or continuous chamber 4' with porous walls covered with steam on the inner side and so shaped that the cycle of fixed gas impinging on it will bring any carbon in suspension into contact with the steam covering and so be converted into gas. The roof of chamber 4' is curved and flattened out at 5' to increase the deflecting surface and cause carbon in the gas stream to contact with steam. The gas stream then passes through or over a heater 11 of any desired construction which serves to heat or reheat the gas to about or over 1800° F. This reheated gas then flows past the spray head 2 to mix with and impart heat to the newly admitted hot oil gas and the mixture continues to circulate in a cycle through the chamber 1. In this manner, the oil gas admitted into the chamber 4 is heated to about 1600° F. and becomes a fixed gas. The fixed gas is withdrawn from the chamber from an outlet 12 in a volume to equal that admitted from the spray head 2. The balance of the fixed gas at about 1600° F. is heated by the heater 11 to over 1800° F., and this fixed gas picks up or entrains the newly admitted oil gas and raises its temperature. If desired, the outer wall 6 of chamber 7 may be heated in any desired manner as by a jacket of hot combustion gases to maintain the steam heated or superheat the same.

In Fig. 3, I have shown an apparatus wherein a similar porous steam sleeve is applied to a device adapted to produce gasoline. A supply of

hot oil gas is fed from a conduit 13 to a spray head 14 and from this head into a chamber 15. The inner wall 16 of this chamber is formed from a porous material, for example, a porous refractory material. A spaced outer wall 17 is arranged to form a steam chamber 18 to which steam is supplied from a conduit 19 controlled by a valve 20. In a manner shown from Fig. 1, the steam passes slowly or oozes through the wall 16 to form a coating of steam on this wall to act as a shield or sleeve of steam around the gas stream above the spray head 14 whereby to prevent any deposit of free carbon on the wall 16 of the chamber 18. A continuous supply of hot fixed gases at about 1100° F. is supplied to chamber 18 from a conduit 21. These gases entrain and mix with the hot oil gas supplied from spray head 14 at about 700° F. and raise this oil gas to a gasoline producing temperature. The mixture of gases is passed through a desired form of dust extractor 22 which serves to separate or gasify any free carbon present in the gas mixture. The mixture of gases is then passed through a liquefying retort 23 where the gasoline portion is condensed. The remaining gases are drawn off at outlet 24 by means of a suction device. If the discarded gases are found to be combustible, they may be burned with air to produce heat for use in the process. I prefer to supply from the conduit 13 hot oil gas under a desired pressure and a proportion of one volume thereof to three volumes of the fixed gases supplied from the conduit 21, preferably also under a suitable pressure. An outlet valve 25 is provided to control the pressure in the chamber 15.

In the gas fixing chamber 4 of Fig. 1, and the gasoline producing chamber 15 of Fig. 3, the velocity of the gas stream should be maintained at a suitable velocity to keep free carbon, if any, in suspension. The quantity of steam and pressure thereof may be regulated. I prefer to main-

tain a steam pressure corresponding to that of four inches of water pressure, though this may be varied according to the porosity of the walls 5 or 16. In Figs. 1 and 3, the heating of the oil gas up to its fixation or gasoline producing temperatures is obtained mainly through convection rather than by any contact with solid substances or by conduction. 5

In the operation of the device shown in Fig. 1, the oxygen is first removed from the chamber 1 and this chamber heated preferably by combustion or other means and steam is thereafter admitted to the chamber 7. Oil gas is then sprayed from the head 2 into chamber 1 at about 700° F. at a suitable pressure. The heater 11 is 15 put into operation to make up for the heat given to the oil gas intake. The oil gases in the chamber 1 become fixed due to their continuous circulation at 1600 to 1800° F. and may be drawn off at outlet 12 as desired and the supply of additional oil gas to replace the fixed gas drawn off will provide a continuous process. 20

What I claim is:

A method of producing a fixed combustible gas which comprises feeding a stream of hot oil gas 25 at about 700° F. together with a larger volume of higher temperature gas into a chamber at one point whereby to fix said oil gas, passing steam through the wall of the chamber adjacent said joint to maintain a shield of steam around the 30 stream of mixed gases drawing off a portion of the fixed gas produced at another point in said chamber, causing the balance of the gas mixture to flow from the last-named point to a third point, applying heat to the balance of gas at 35 said point to reheat this balance up to its gas fixing temperature of about 1800° F., then passing said balance of gas in a closed cycle back to said first point and again feeding hot oil gas to said balance of gas. 40
